UNITED STATES PATENT OFFICE

152,471

DESIGN FOR A PAIR OF SCISSORS

Paul L. Hartnett, Leominster, Mass.

Application March 7, 1947, Serial No. 137,456

Term of patent 7 years

(Cl. D22—5)

To all whom it may concern:

Be it known that I, Paul L. Hartnett, a citizen of the United States, residing at Leominster, in the county of Worcester and State of Massachusetts, have invented a new, original, and ornamental Design for a Pair of Scissors, of which the following is a specification, reference being had to the accompanying drawing, forming part thereof.

Fig. 1 is a front elevational view;

Fig. 2 is a rear elevational view showing the scissors in open position; and

Fig. 3 is an edge view of a pair of scissors, showing my new design.

I claim:

The ornamental design for a pair of scissors, as shown.

PAUL L. HARTNETT.
